WILHELM HENNING PETERSEN, OF LUDVIKA, SWEDEN, ASSIGNOR TO ALLMANNA SVENSKA ELEKTRISKA AKTIEBOLAGET, OF VASTERAS, SWEDEN, A CORPORATION OF SWEDEN.

QUICK-ACTING MECHANISM FOR TIME RELAYS.

Application filed January 11, 1923. Serial No. 611,990.

Relays for releasing purposes which are destined to act only after the operating value of current has been sustained for a certain period of time, said time being either 5 independent of the current or variable inversely thereto, are either of the type which are quick-acting in itself, but provided with a retarding device based for instance upon fluid friction or clock-work movement, or of 10 the type where the primary operative member normally moves at a slow speed. The latter is especially the case in the induction type of relays, where a motor armature or Ferraris disc moves at a speed varying with 15 the current, in general substantially proportioned thereto.

In such relays, it has been found advisable to provide a special quick-acting mechanism at the end of the path of said operative 20 member to actuate a pair of contacts or other releasing device, and the chief object of my present invention is to provide such a device.

While the said quick-acting device may 25 be of different design, it has been found preferably to construct it to perform its quick-acting movement under magnetic action. Especially when the primary operative member of the relay is moved under 30 magnetic action, as for instance in induction type relays, a simple and effective solution of the quick-action problem may be had by providing a magnetic shunt to a magnet acting upon said primary member.

35 A form of the invention, based upon the last-mentioned principle, is illustrated in the accompanying drawing, where Figure 1 shows a relay in a front view with certain parts broken away, which are non-essential 40 to the invention. Figure 2 shows the principle parts of the quick-acting mechanism in an end view.

Referring to drawing, 1 is an induction 45 disc rotating under the influence of an electromagnet having a core 2, a main coil 3, and two short circuit coils 4 embracing portion of its poles for creating an auxiliary field phase. The induction disc is journaled in a frame 5, which is capable of being 50 displaced in the manner described in my pending application No. 472,848, for bringing the worm 6 on the shaft of said disc into engagement with the toothed segment 7, as soon as the current traversing the coil 3

exceeds a certain value. When this is done, 55 the disc (which is supposed to be continuously rotating) imparts its motion to the toothed segment which is then lifted. At the end of its upward motion, the segment is intended to perform a releasing action, 60 for instance by bringing a pair of contact pieces 8, 9 into contact with each other. Since the motion of the segment, however, is comparatively slow, and the motion of the releasing device, as the contacts, preferably should be quick, there is interposed between these devices a quick-acting mechanism. In the form shown, this mechanism consists of a piece 10, insulated from the 65 contact piece 8 by means of a washer 11 secured to the latter, said piece 10 being mounted on a magnet armature 12. Said armature is pivotally mounted in an iron yoke 13 by means of pin 14. The two magnetic pieces 12 and 13 form part of a magnetic path shunting the air gap of the electromagnet core 2, said shunt path comprising 70 also a longitudinal piece 15 and a cross piece 16. In the form shown, the yoke 13 is solid, while the piece 15 is partly solid, 75 partly laminated, and the piece 16 entirely laminated. This has proved to be an appropriate form in practice. 17 is a piece of non-magnetic metal serving to brace the upper end of the piece 15 with the yoke 13. 80

The armature 12 extends to both sides of its pivoting point and is separated from the main core 2 of the electromagnet by approximately equal air gaps at both ends. However, it is normally prevented from moving 85 in more than one direction by an adjustable stop screw 18. When a projection 19 on the segment 7 strikes the piece 10 and raises the corresponding end of the armature 12, thus increasing one air gap and reducing 90 the other, the force of attraction in the latter will soon overcome that of the former, which normally is supposed to be a little predominant, and cause a sudden attraction 95 of the corresponding end of the armature, the other end of which then strikes the movable contact piece 8 and brings it into contact with the fixed piece so that the relay will perform its releasing action. 100

The end of the armature 12 which thus is intended to be attractive to the core may be provided with a "shading" coil 20 to prevent its vibrations when attracted. On the 105

other end which always is at a distance from the corresponding part of the core, such a shading coil is generally not necessary.

The chief advantage of balancing the armature around its centre and causing the core to attract both ends thereof is that a mechanical action from outside is always necessary for initiating the movement of attraction. If the armature is acted upon only or predominantly by the same pole, which is intended to eventually attract it, and normally kept away from that pole only by mechanical means, the result of a heavy overload will be that it is attracted without such initiating mechanical action, and thus in case of such an overload the relay will act instantaneously, independently of the time setting. In some cases this may be desirable, and it is easily accomplished even in the case of a balanced armature by an appropriate use of the stop screw 18. If, by means of this screw, the corresponding end of the armature is approached to the main core so that the attraction on this end will be normally a little in excess of that on the other—which excess may then be balanced by the overweight of the other end—or even if this attraction is normally less, but will be in excess at a certain overload on account of the variable reluctance of the different portions of the magnetic path, the action of the relay in case of such an overload will be instantaneous. The stop-screw 18 thus will have two different positions for two different kinds of action of the relay. For being safely held in these different positions, it may be provided with a knurled head 21 engaged by a spring piece 22 and also slits or other marks on its top to clearly show the position set.

I claim as my invention:—

1. In time relays, an electromagnet having laminated iron core, a metallic member capable of being moved in an air gap of said core by induction from said electromagnet, an operative member connected to said induction member by speed reducing gear, a movable magnetic core portion shunting said air gap, and a member connected to said movable core portion and lying in the path of said operative member.

2. In time relays, an electromagnet, an operative member capable of being moved at slow speed under the action of said electromagnet, a movable core portion of the said electromagnet forming two magnetically parallelled air gaps, and mechanically associated with said operative member so

as to move quickly when actuated thereby.

3. In time relays, an electromagnet, an operative member capable of being moved at slow speed under the action of said electromagnet, a movable core portion of said electromagnet forming two magnetically parallelled air gaps and mechanically associated with said operative member and adjusting means for the said movable core portion for reducing one of said air gaps and increasing the other.

4. In time relays, an electromagnet having laminated iron core, a metallic member capable of being moved in an air gap of said core by induction from said electromagnet, an operative member connected to said induction member, an iron core portion magnetically shunting said air gap, an armature pivotally mounted in said core portion and separated from the fixed iron core by air gap at both ends, and a member connected to said armature and lying in the path of said operative member.

5. In time relays, an electromagnet, an operative member moving through a path at a low speed under the influence of the current of said electromagnet, an armature pivoted at its centre and attracted at both ends by portion of said electromagnet, having the same polarity, a projection of said armature lying in the path of said operative member, and a movable contact lying in the path of said armature.

6. In time relays, an electromagnet having three magnetically parallel air gaps, one of said air gaps being of constant width and embracing an induction disc, while the two others are limited by a pivoted portion of the core so as to be mutually variable, an adjusting device for regulating the initial position of said pivoted portion, and a movable contact actuated by said pivoted portion.

7. In time relays, an electromagnet having a laminated main iron core with an air gap, an induction disc movable in said air gap, a speed reducing gear connecting said disc to an operative member, an additional core portion of the electromagnet bridging said air gap, and having two lateral arms, an armature pivoted in said additional core portion and adapted to be attracted by either arm thereof, a projection of said armature lying in the path of said operative member, and a movable contact arm lying in the path of said armature.

In testimony whereof I have signed my name to this specification.

WILHELM HENNING PETERSEN.
